S. MANUEL.

GRAIN CAR DOOR.

APPLICATION FILED APR. 10, 1914.

1,143,846.

Patented June 22, 1915.

UNITED STATES PATENT OFFICE.

SAMUEL MANUEL, OF SALTCOATS, SASKATCHEWAN, CANADA.

GRAIN-CAR DOOR.

1,143,846.

Specification of Letters Patent. Patented June 22, 1915.

Application filed April 10, 1914. Serial No. 831,092.

To all whom it may concern:

Be it known that I, SAMUEL MANUEL, a subject of the King of Great Britain, residing at Saltcoats, in the Province of Saskatchewan, Dominion of Canada, have invented certain new and useful Improvements in Grain-Car Doors; and I do hereby declare the following to be a full, clear, and exact description of the invention, such as will enable others skilled in the art to which it appertains to make and use the same.

This invention relates to improvements in doors for grain cars.

One object of the invention is to provide a sectional door formed of a plurality of independently movable plates which are capable of being nested in a suitable bracket above the door.

Another object is to so form each of the sections of the door that they can be readily grasped to be moved into either closed or open position.

Other objects and advantages will be apparent from the following description, when taken in connection with the accompanying drawings.

In the drawings: Figure 1 is a front elevation of the door showing the same in closed position. Fig. 2 is a similar view showing the door partly closed. Fig. 3 is a vertical section on the line 3—3 of Fig. 1. Fig. 4 is a perspective view of one of the plates removed.

Referring particularly to the accompanying drawing, 10 represents a pair of slideways mounted on the sides of the doorway of the car, the upper ends being curved upwardly and inwardly, as clearly shown in Fig. 3, and secured to the inwardly extending brackets 12 above the doorway. The lower portion of the inner end of each of the slideways is bent to form a recess or bracket 13. A plurality of elongated metal plates 14 are disposed crosswise of the doorway and provided with a slightly twisted longitudinally extending reduced end portions 15, these end portions being slidably disposed in the slideways 10 as clearly shown. The upper longitudinal edge portion of each of the plates is bent outwardly at right angles to form a flange 16, while

the lower edge portion of each of the plates is bent inwardly at right angles to form a flange 17. Each of the slideways has an attaching flange 18, and between this flange 55 and the body of the slideway is an inset angular recess which receives the ends of the flanges 16 and permits them to slide freely up or down.

It will be noted that the twisted end portions 15 rest on the corresponding portions of the plates below. The slides have their grooves of such width that the twisted portions 15 will easily move up and down, but not wide enough to permit them to pass the 65 extensions of another plate.

When the door is in full open position all of the plates are nested in superposed relation within the support or bracket 13. When in this elevated position, and it is desired to close the door, the innermost flange 70 17 can easily be grasped to lift the topmost plate up into the curved parts of the slideways. It will also be noted that the upper flanges 16 provide ready finger-holds to 75 raise and lower the plates in the slideways. Thus, at all times, the plates can be quickly and easily grasped for manipulation.

What is claimed is:

The combination with grooved slideways 80 mounted on opposite sides of the car door, of a plurality of metal plates disposed between the slideways, and each having reduced end portions disposed in the grooves of the slideways, such reduced portions being deflected so that they lie in a common plane while the bodies of the plates lie in parallel inclined planes, the lower edge portion of each of the plates being bent inwardly at right angles to the plate and the 85 upper edge portion being bent outwardly at right angles whereby convenient finger holds are provided to facilitate the manipulation of the plate, said plates being adapted to be moved to the tops of the slideways and 90 into a nested pile.

In testimony whereof, I affix my signature, in the presence of two witnesses.

SAMUEL MANUEL.

Witnesses:

FLORENCE FEA,
DAVID FOULIS.
